REMOVABLE BOTTLE CLOSURE DEVICE

Axel W. Anderberg, Los Angeles, Calif.

Application August 25, 1947, Serial No. 770,489

2 Claims. (Cl. 215—82)

1

This application relates to bottle closure means adapted for use on bottles having a mouth or neck end so shaped as to normally be sealed by a closure device of the "crown" type. The device of this invention is intended primarily for use in the resealing of such bottles where the original closure has been removed and it is desired to effectively and hermetically seal the residual contents of the bottle, the device having its maximum utility where it is desired to seal the bottle against the escape of gas under pressure, i. e. a gas such as a carbonating gas which is commonly employed for beverages.

One of the particular objects of the invention is to provide a removable bottle closure having a clamping lever provided with a bead-engaging shoulder structure which is adapted to engage a coacting bead on the bottle at two spaced points of contact during application of the closure to the bottle, and to engage upon such bead over an elongated zone in excess of one-half the circumferential length of such bead when the closure is in fully applied position. More particularly, the bead-engaging shoulder is so shaped and so carried upon the clamping member as to resiliently engage upon the bottle during the above-mentioned engagement at spaced points of contact, yet rigidly engage upon the bead in the fully applied position.

I am appreciative of the fact that numerous forms of bottle closures have heretofore been proposed for the purpose of resealing a bottle from which a crown type of closure has been removed, but for the most part, insofar as I am able to determine, the prior proposed forms of closures inadequately seal the bottle against the escape of gas under the pressure which develops in the bottle after the seal has been applied. It will be apparent, upon consideration, that upon sealing a bottle which is open to the atmosphere, the sealing pressure when the closure is being applied upon the open mouth of the bottle need be but nominal inasmuch as the dissolved gas in the beverage or other contents of the bottle cannot develop a superatmospheric pressure condition, but after the bottle has been sealed, some of the dissolved gas will come out of solution, with a consequent increase in internal pressure on the closure. For the most part, the prior suggested forms of closure means of the type with which this invention is concerned have relied upon the provision of shoulder means which will engage upon the outer rim or bead at the bottle mouth, i. e. the bead upon which the conventional crown-type of closure engages, and owing to the fact that

2

it is substantially impossible to provide any cam or lever action which will engage upon the nether portion of this bead at more than two spaced points during the actual application of the closure (unless a closure of the crown type is employed so as to engage about substantially the entire periphery of the bottle), difficulty has been had in applying a sealing pressure which is adequate to prevent escape of gas from the bottle under the developed pressure condition without producing such an intensification of stress upon the bottle rim as to be likely to cause fracture thereof at the position of the aforesaid spaced points of contact.

According to the present invention the desired sealing pressure is obtained by causing the locking lever portion of the structure to engage a portion of the bottle neck which is materially removed from the mouth, at a position where the bottle is more adapted to withstand the stresses imposed by the closure upon application. Bottles adapted to receive the crown type seal are customarily provided with an inner or second reinforcing bead which is spaced from the outer bead which receives the crown type seal. The location of this second bead is subject to minor variation in an axial sense and it is one of the objects of this invention to provide a closure structure which will be effective to lock upon this second bead in spite of such minor variations in the location thereof as may result in the products of different manufacturers.

A further object of the invention is to provide a bottle closure having a cap portion carrying a resilient sealing member which is adapted to fit over the open end of a bottle in sealing relation to the opening therein, together with a clamping member pivotally attached to the cap portion at two diametrically located points, said clamping member being so shaped as to depend from the points of pivotal support in a relation subtending somewhat more than one-half the circumference of the bottle neck. The clamping member is provided with an inwardly directed shoulder positioned for engagement with the above-mentioned second bead of the bottle neck within a zone extending substantially the full subtending expanse of the clamping member about said neck and is further provided with means stiffening the medial portion of the length of said inwardly directed shoulder member, said stiffening means being terminated short of the end portions of said inwardly directed shoulder member at a position such as to cause the end portions of said shoulder means which extend beyond the half-circum-

ference to be resiliently biasable in radially outward directions.

The above and other features of this invention will be brought out in the ensuing description of a preferred embodiment, taken with the accompanying drawings, or will be apparent therefrom. Referring to these drawings:

Fig. 1 is a fragmentary perspective view of the neck portion of a bottle provided with a closure of this invention;

Fig. 2 is a diametrical vertical section as taken on line 2—2 in Fig. 1;

Fig. 3 is a diametrical vertical section taken at right angles to that of Fig. 2, as on line 3—3 therein;

Figs. 4 and 5 are transverse sections as taken on lines 4—4 and 5—5, respectively, in Fig. 3; and

Fig. 6 is a fragmentary view showing the neck of a bottle upon which a closure of this invention is being applied, the closure being shown at the beginning of the clamping or sealing movement of the clamping member.

Referring to the drawings a conventional glass bottle is shown at 1 provided with a neck portion 2 having an outer bead 3 upon which the conventional crown seal type of closure is adapted to be applied, and a second bead 4 spaced below the outer bead 3. The spacing of the bead 4 from the bead 3, as above described, and the general contour of the lower portion of this second bead, has been found to be fairly consistent in the various bottles from different manufacturers, the maximum variation having been found to be on the order of about $\frac{1}{32}$ " insofar as the spacing of the nether shoulder portion of the second bead from the first bead is concerned. It will be noted that the bottle neck is materially thickened at and slightly above the position of the second bead 4, making the bottle structure much more capable of resisting the stresses resulting from the application of the closure if such closure stresses are applied at the position of the bead 4 rather than at the position of the bead 3.

The closure device of this invention is illustrated as comprising a cap portion 5 provided with a rim portion 6 having an internal diameter only slightly greater than the outer diameter of the bead 3 (the dimensions of this bead being quite consistent in the trade). The rim portion 6 is preferably of such length as to normally extend to slightly below the bottom of the bead 3, in a covering relation thereto. The cap portion 5 carries a washer 7 which is necessarily of a resilient material which will effectively seal upon the bead 3 when the closure is clamped in place. The material forming the washer 7 is preferably of a rubber-like nature, preferably a composition which will maintain its resilience (i. e., property of resilient deformation under applied pressure) over a relatively long period of use and which will be substantially impermeable by carbon dioxide.

A clamping lever 8, preferably formed of relatively stiff, spring-like metal, is pivotally attached to the cap portion 5, as to the rim portion 6, through the agency of rivets 9, the rim portion 6 of the cap portion being preferably bumped out as at 11, into which the rivets may be recessed. The position of pivotal mounting of the clamping lever 8 upon the cap portion 5 is preferably so selected as to be located below the position of sealing engagement of the washer 7 upon the outer bead 3 during the clamping operation, as will be apparent from the drawings. The clamping lever 8 is provided with a depending skirt portion 12 of such length as to extend downwardly

past the position of the second bead 4 in use, and preferably terminates in a downwardly and outwardly extending thumb lever portion 13. The skirt portion 12 is of such length in a circumferential sense as to encompass somewhat more than the half-circumference of the bottle neck, and to this end is provided with a pair of projecting portions 14 which have their maximum projection at a position just below the location of the bead 4.

10 The skirt portion 12 is provided with an inwardly directed shoulder member 15, such as may be formed by embossing a groove 16 inwardly upon the skirt 12, which shoulder member, as may be seen more particularly in Figs. 4 and 5, is adapted to encompass somewhat more than the half-circumference of the bottle neck below the bead 4. The portions 17 of the shoulder 15 which are located forwardly of the half-circumference of the bottle, i. e., at the position of the projecting portions 14, are carried inwardly so as to cam over the bottle diameter by resilient deformation of the clamping lever, as such lever is moved into fully clamped position.

15 The skirt portion 12 is materially stiffened by the provision of the shoulder 15, but is obviously subject to expansion in a radial sense at the position of the forward portions 14 as the shoulder portions 17 are brought past the bead 4 (see Fig. 6) in the clamping operation. In order to restrict this radial expansion of the skirt 12 to substantially the projecting portions 14, and the shoulder portions 17, I provide a circumferentially extending stiffening bead 18 adjacent the shoulder 15, as between the shoulder 15 and the pivot axis as defined by the rivets 9. The stiffening bead 18 is preferably embossed outwardly so as not to interfere with the clamping operation by engagement upon the portion of the bottle neck between the beads 3 and 4. This stiffening bead 18 is preferably stopped short of the half-circumference of the skirt 12, and is thus of less circumferential length than the shoulder 15, thereby serving to restrict the radial expansion of the skirt member under resilient deformation substantially within the zone indicated by the double-headed arrow F in Fig. 1, at each side of the closure.

20 The skirt 12, when moved from the position of Fig. 6 into the position of Fig. 3, will first engage the bead 4 at the projecting portions 17 of the shoulder 15, causing the skirt portions 14 to expand outwardly in the direction shown by the small arrows f in Fig. 2, and permit the shoulder portions 17 to pass the bead. As the skirt portion is moved more fully into the position of Fig. 3, the shoulder portions 17 flex inwardly into position under the bead 4 and past the diametral dimension of the bottle neck, clamping inwardly upon the bottle in engagement with the nether contour of the bead, and at the same time, the portions 19 of the shoulder 15 intermediate the shoulder portions 17 move into position rigidly engaging the nether surface of the bead 4 as shown in Fig. 3, engaging so much of the encompassed portion of the bead 4 as the symmetry of the contour of this bead will permit and thus distributing the clamping load onto a zone extending over more than one-half of the circumferential length of this bead. In clamping position, the skirt portion 12 of the clamping member is very rigid in directions tending to distort the shoulder 15 upwardly or downwardly, so as to cause a quite rigid engagement of such shoulder upon the bead 4 wherever the mutual conformations of the bead and

shoulder will permit. During the movement of the clamping lever to fully clamped position the washer 7 is compressed onto the bead 3, and the resiliency of this washer serves to maintain the upwardly directed clamping effort of the shoulder 15 upon the bead 4 while the shoulder portions 17 further constrain the clamping lever in the position of Fig. 3.

In the event that the bead 4 is located somewhat below the position shown in the drawings (within the dimensional variation above referred to) the shoulder 15, including the portions 17, will grip upon the bead 4 at a relatively higher position than is illustrated and on a contact line of somewhat greater radius. This results in greater resilient deformation of the skirt portions 14, causing the shoulder portions 17 to exert a greater inwardly directed holding action in proportion.

It will be appreciated that the above-described construction is intended only to be illustrative of the best mode of making and using the device of my invention, and I do not consider the invention as limited to the precise details herein set forth, but rather to the scope of the subjoined claims.

I claim:

1. A closure device for bottles provided with a neck portion of circular cross-section having an outer bead adapted for reception of a closure of the "crown" type, and an inner bead spaced from and parallel to said outer bead, which comprises: a cap member provided with a resiliently compressible sealing member adapted for engagement with the outer surface of said outer bead of such bottle neck, and a depending rim portion adapted to fit over said outer bead; a clamping member; pivot means on said rim portion of said cap member and on said

clamping member intersecuring said members for pivotal movement of said clamping member into and out of clamping position about said bottle neck; said clamping member being formed of spring-like metal and comprising a skirt portion of such length as to extend downwardly from the position of said pivot means past the position of said inner bead of said bottle, and of such length in a circumferential sense as to encompass in excess of the half-circumference of said bottle neck upon pivotal movement of said clamping member into clamping position; an inwardly directed shoulder on said skirt member positioned to be located in contact with said inner bead at the side thereof removed from said outer bead when said clamping member is in said clamping position, said shoulder being of a circumferential length greater than the half-circumference of said bottle neck at the position of said inner bead, and the end portions of said shoulder being provided with projecting portions adapted to cam over the bottle neck diameter upon movement of said clamping member into said clamping position by resilient outward deformation of said skirt member at the position of said shoulder end portions.

2. A construction as set forth in claim 1, said skirt portion being further provided with a stiffening bead located adjacent said shoulder and extending circumferentially not materially in excess of the half-circumference of said skirt portion so as to be of less length than said shoulder, to thereby cooperate with said shoulder to stiffen said skirt portion intermediate said end portions against radial deformation thereof, while leaving said end portions capable of resilient outward deformation.

AXEL W. ANDERBERG.
